UNITED STATES PATENT OFFICE.

GEORGE W. FASSETT, OF MIDDLEBURY, AND RINALDO A. WHITTIER, OF HANCOCK, VERMONT.

GLUING-MACHINE.

SPECIFICATION forming part of Letters Patent No. 690,847, dated January 7, 1902.

Application filed March 6, 1901. Serial No. 50,085. (No model.)

To all whom it may concern:

Be it known that we, GEORGE W. FASSETT, residing at Middlebury, and RINALDO A. WHITTIER, residing at Hancock, in the county 5 of Addison and State of Vermont, citizens of the United States, have invented a certain new and useful Gluing-Machine, of which the following is a specification, reference being had therein to the accompanying drawings.

10 This invention relates to gluing-machines, the object in view being to provide a machine embodying, in connection with an adjustable slat-holding rack, feeding mechanism for successively transferring the slats to the gluing 15 mechanism and a gluing device comprising glue-applying disks adjustable relatively to each other and adapted to spread the glue upon the slats at various intervals and in lines extending parallel to each other and 20 transversely of the slat.

It is also an important object of this invention to provide means whereby the machine is adapted to accommodate slats of different lengths, widths, and thicknesses; also, to provide 25 adjustable slat-carriers and operating mechanism therefor, and also to construct the gluing mechanism in such manner that the glue-applying disks are capable of being adjusted relative to each other for the purpose 30 of applying the glue at proper intervals to each slat as it is moved by the feeding mechanism.

Another object of the invention is to provide, in connection with reciprocatory actuating-straps, carriers forming part of the feeding mechanism, which carriers are adjustably associated with the actuating-bands for changing the throw of the carriers.

40 A further object of the invention is to provide a jointing-hammer which is connected with the same operating device which actuates the feeding mechanism, so that the said hammer and feeding mechanism will be simultaneously operated.

45 With the above and other objects in view, which will be better understood as the description proceeds, the invention consists in the novel construction, combination, and arrangement of parts hereinafter fully described, illustrated, and claimed.

In the accompanying drawings, Figure 1 is a front elevation of a gluing-machine constructed in accordance with the present invention, parts thereof being broken away for better illustration. Fig. 2 is a vertical transverse section through the machine. Fig. 3 is a horizontal section through the machine. Fig. 4 is a detail perspective view of the self-adjusting back-stop. Fig. 5 is a similar view of one of the guides for the jointing-hammer. Fig. 6 is an enlarged detail perspective view of one of the reciprocatory slat-carriers and a portion of the actuating-band therefor. Fig. 7 is a detail cross-section through the same, showing the clamp which connects the slat-carrier adjustably to the actuating-band. Fig. 8 is a fragmentary plan view showing the means for driving the shaft which carries the glue-applying disks. Fig. 9 is a detail cross-section through the jointing-hammer and a portion of the frame, showing the means for guiding the hammer. Fig. 10 is a detail perspective view of one of the slats.

Similar numerals of reference denote like parts in all the figures of the drawings. 75

The machine contemplated in this invention is especially designed with reference to the gluing and jointing of the comb frames or sections of a beehive, which frames or sections, as is well understood, are of open rectangular form and which are ordinarily constructed from a slat 1, (illustrated in detail in Fig. 10,) such slat consisting of a strip of wood of the necessary length, breadth, and thickness, which, preparatory to the formation of the comb frame or sections, is passed through a suitable machine, which forms therein the transversely-extending V-shaped kerfs 2, which define three of the corners of the comb frame or section, and the mortises 80 and tenons 3 at the extremities of the slat, which interlock with each other when the slat is folded and form a lock corner-joint. 85

The mechanism hereinafter described is adapted to apply glue to the several kerfs 2 and ends 3 as they are fed outward by suitable feeding mechanism from a slat-holding rack, the extremities of the slat being subsequently forced into engagement with each other by means of a jointing-hammer, which 90 95 100

may be propelled with any desired force against the corner of the frame or section where the lock corner-joint occurs.

The machine comprises, essentially, a pair 5 of end uprights 4, which are provided at the bottom with supporting base-timbers 5 and connected by suitable longitudinal frame-bars 6 and 7, the bars 6 forming a support for a series of slat-supporting rails 8, which rest 10 upon the bars 6 and are secured thereto in any convenient manner. The rails 8 are preferably constructed of sheet metal and provided with upstanding flanges 9, upon which the slats slide as they move forward 15 when actuated by the feeding mechanism. The end frames 4 are further connected at their upper ends by a longitudinal hanger-bar 10, provided with longitudinal slots 11 to receive clamping-bolts 12, which are inserted 20 through the upper extremities of a pair of end guides 13 and provided with thumb-nuts 14, so that the upper ends of the end guides 13 may be adjusted lengthwise of the hanger-bar 10 for varying the distance between the 25 end guides and accommodating slats of different lengths, the parts 13 forming the ends of the slat-holding rack, as shown in Figs. 1 and 3. The lower ends of the guides 13 are adjustably connected to a guard or presser-bar 15, which is provided with slots 16 to receive clamping-bolts 17, provided with thumb-nuts 18. Each of the end guides 13 is also connected to one of the longitudinal frame-bars 6 by means of a clamping-bolt 19, passing 30 through said bar 6, and a pendent extension 20 of the end guide, as shown in Fig. 2. Provision is thus made for securely fastening the upper and lower ends of the end guides 13 and at the same time rendering said 35 guides adjustable toward and away from each other for accommodating slats of different lengths. The guard or presser-bar 15 is provided with a forwardly-extending flange 21, which serves to hold the slats downward in 40 engagement with the gluing devices as the slats are successively moved forward by the feeding mechanism hereinafter described.

At their front edges the guides 13 are provided with face-plates 22 of greater width 45 than the thickness of the end guides, so as to provide inwardly-extending flanges or stops 23, which will lie in front of the forward edges of the slats, as shown in Figs. 1 and 3. The rear edges of the slats are held by means 50 of self-adjusting back-stops 24, each of which is provided with an angular flange 25, adapted to engage directly with the rear edges of the slats, as shown in Fig. 3, the body of each back-stop being provided adjacent to its opposite ends with inclined or oblique slots 26, which receive clamping-bolts 27, passing into one of the end guides 13. After placing a pile of slats within the rack the back-stops 24 are engaged with the bolts forming members of the clamping devices 27, and, on account of the inclination of the slots 26, the back-stops will gravitate toward the slats un-

til the flanges 25 are brought into engagement therewith, whereupon the clamping device 27 may be tightened. In this way provision is made for accommodating slats of different widths.

The mechanism for feeding the slats to the gluing device comprises a plurality of slat-carriers 28, each of which comprises the upstanding flanges 29, preferably recurved at their upper edges to form the depending guide-strips 30 for engaging one of the members of the clamp whereby the carrier is secured to its actuating-band. The clamp consists of a plate 31, having upturned end portions 32, between which is received a cap 33 in the form of a plate having upturned edges or flanges 34, which are received behind the guide-strips 30 in order to render the clamp 35 adjustable lengthwise of the slat-carrier. A clamping-screw 35 passes through the cap 33 and engages a nut 36, held between the clamp and cap, the lower end of the clamping-screw bearing against the body of the clamp 31, so as to force the latter into firm engagement with a portion of the actuating-band 37, which passes through slots 38 in the bottom 39 of the slat-carrier, which slots are spaced apart, so as to allow a portion of the band to extend over the top of the floor or bottom 95 of the carrier, as illustrated in Figs. 6 and 7. By loosening the screw 35 the slat-carrier may be adjusted lengthwise of the actuating-band 37 for the purpose of varying the throw 100 of the slat-carrier and accommodating the same to slats of different widths. The slat-carrier is also equipped with a feed-dog 40, which for convenience is shown in the form of a spring having one end secured to the 105 body of the carrier and its free end extended sufficiently above the top of the carrier to engage the lowermost slat in the slat-holding rack in a manner which will be understood by reference to Fig. 2.

Motion is imparted to the actuating-band 37 by means of a pair of oscillatory members 41 and 42, preferably in the form of rollers suitably journaled in or on the machine-frame just beneath the rails 8 and carriers 28, as shown in Fig. 2. Each of said rollers is provided with a longitudinal groove 43 to receive one of the extremities of the actuating-band 37, which may be adjusted to any point lengthwise of the groove 43 and held 120 by means of a wedge 44 or the equivalent thereof, which is inserted into the groove. In this way provision is made for the lateral adjustment of the slat-carriers, so that they may be brought into any desired relation to 125 the slats upon which they operate. The roller 41 is reduced by grooving the same, as shown at 45, to receive a roller-operating belt 46, which extends downward and connects with an operating device, preferably in 130 the form of a foot-lever 47, fulcrumed at 48 on the machine-frame. By depressing the lever 47 rotary motion is imparted to the roller 41, so as to cause the actuating-bands

37 and the slat-carriers to move forward and feed a slat to the gluing mechanism. The band is retracted by the roller 42, which is provided with an inclosed actuating or reTRACTING SPRING 49, having one end connected to the body of the roller and its other end connected to the shaft upon which the roller is journaled, as shown in Fig. 3.

The gluing mechanism comprises a glue-trough 50, having a lower compartment for holding hot water and an upper compartment for containing the glue in liquid form, the two compartments being divided by a dished partition 51, centrally concaved to agree with the circumference of the gluing-disks, as shown in Fig. 2, so that the disks will take up the glue as long as any glue remains in the trough. The trough 50 may be of any suitable length and is adapted to extend beneath all of the gluing-disks. Arranged above the bottom of the glue-receiving compartment of the trough is a shaft 52, extending lengthwise of the trough and having mounted thereon a series of glue-applying disks 53, each of which is provided with a set-screw 54, so that said disks may be adjusted relatively to each other and placed at any point on the shaft 52, according to the location of the kerfs 2 of the slat 1. Each disk except the end one has its periphery beveled or chamfered from only one side, as shown at 54, in order to apply glue only to one of the inclined sides of the kerfs 2, it only being necessary to glue one of the walls 35 of each kerf. As the shaft 52 revolves the glue-applying disks take up the glue and spread it within the kerfs 2, said glue-applying disks being actuated to revolve preferably in a direction opposite to that in which the slat is fed by the slat-carrier. Motion is imparted to the shaft 52 by means of a belt 55, which passes around the rollers 41 and 42 and also one or more times around a small drum 56 at one end of the shaft 52, as illustrated in Fig. 8, wherein the glue-trough is shown as provided at one end with a filling-nozzle 57. Beneath the trough 50 is arranged a suitable heater 58, the same being supported upon a vertically-adjustable shelf 59, which enables different forms of heaters to be employed and raised or lowered, so as to have more or less effect upon the water within the lower compartment of the glue-trough.

55 After the slats have had the glue applied thereto in the manner described they are folded one by one into the usual rectangular form and placed by hand upon a table or rest 60, arranged near one end of the machine and 60 at or adjacent to the front thereof, as shown, said table being provided with the upstanding flanges 61 for properly positioning the frame or section. Above said table or rest is arranged a vertically-reciprocating jointing-hammer 62, which is mounted to slide between the flanges 63 of a pair of parallel guides 64. The inner flanges 63 of the guides

are sufficiently offset from the end frame 4, to which the guides are applied, to provide for the attachment to the inner side of the hammer of an operating connection 65, which is attached at its upper end to the hammer by means of a bolt or other suitable fastener 66 and at its lower end to the operating device 47, the said hammer-operating connection passing at intermediate points around suitable direction-pulleys 67, journaled on the machine-frame. The hammer is moved downward by pressing upon the foot-lever 47, and when the foot-lever is released the hammer is moved upward by means of a retracting-spring 68, connected at one end to the hammer and at the opposite end to a fixed part of the frame.

From the foregoing description it is thought that the operation of the machine will be readily understood. The operator by depressing the foot-lever 47 operates the feeding and gluing mechanisms, and at each stroke of the lever 47 a slat is fed forward by the slat-carrier and glue applied thereto by means of the glue-applying disks 53. The operator then grasps the slat and folds the same into rectangular shape and places the same on the rest or table 60, at the same time bringing the interlocking extremities of the slat into alignment with each other. In the next stroke of the foot-lever 47 the jointing-hammer 62 is thrown downward, so as to jam the interlocking extremities of the slat firmly together, and simultaneously therewith an additional slat is fed forward by means of the slat-carriers. In this manner the slats are quickly fed forward, glued, and formed into rectangular shape and securely united at the lock-corner, enabling the comb frames or sections to be manufactured with great rapidity. After the desired number of frames or sections have been manufactured the glue may be withdrawn from the glue-trough by means of a drain-spout 69, inclining downward from the bottom thereof and provided with a suitable stopper 70.

It will be apparent that the machine hereinabove described is susceptible of considerable variation in detail without departing from the principles of the present invention, and we therefore reserve the right to make such changes as come within the scope of the appended claims.

Having thus described the invention, what is claimed as new, and desired to be secured by Letters Patent, is—

1. In a gluing-machine, the combination with a slat-holding rack, and a glue-applying device, of slat-feeding mechanism including a reciprocatory slat-carrier, a reciprocatory carrier-actuating band, and means providing for the lateral adjustment of the band.

2. In a gluing-machine, the combination with a slat-holding rack, and a glue-applying device, of slat-feeding mechanism including a reciprocatory slat-carrier, a band for actuating said carrier, a roller for driving said

- band, and means for adjusting the actuating band lengthwise of the roller and correspondingly adjusting the slat-carrier laterally.
3. In a gluing-machine, the combination with a slat-holding rack, and a glue-applying device, of slat-feeding mechanism including a reciprocatory slat-carrier, an oscillatory roller, a carrier-actuating band having one end fastened directly to said roller, and means for retracting said band.
4. In a gluing-machine, the combination with a slat-holding rack, and a glue-applying device, of slat-feeding mechanism including parallel oscillatory members, a band actuated by said members and having its ends fastened thereto, and a slat-carrier operatively connected with and actuated by the band.
5. In a gluing-machine, the combination with a slat-holding rack, and a glue-applying device, of slat-feeding mechanism including parallel oscillatory rollers, a band connecting said rollers, a slat-carrier actuated by said band, a belt for actuating one of the rollers, and a spring for winding the other roller.
- 25 6. In a gluing-machine, the combination with a slat-holding rack, and a glue-applying device, of slat-feeding mechanism including an oscillatory roller having a longitudinal groove, a reciprocatory slat-carrier, and a carrier-actuating band adjustably fitted and held in the groove of the roller.
7. In a gluing-machine, the combination with slat feeding and gluing mechanism, of a vertically-slidable jointing-hammer, a work-table beneath and in the path of the hammer, and means for simultaneously actuating the hammer and slat-feeding mechanism.
8. In a gluing-machine, the combination with slat feeding and gluing mechanism, of a spring-retracted vertically-slidable jointing-hammer, parallel guides in which the hammer slides, a work-table beneath and in the path of the hammer, and means for simultaneously actuating the hammer and slat-feeding mechanism.

In testimony whereof we affix our signatures in presence of two witnesses.

GEORGE W. FASSETT.
RINALDO A. WHITTIER.
